Specification for Design.

Patented July 27, 1909.

Application filed November 30, 1908. Serial No. 465,452. Term of patent 7 years.

To all whom it may concern:

Be it known that I, KARL LUDWIG PRINZ, a subject of the Emperor of Austria-Hungary, residing at Reinprechtsdorferstrasse 48, Vienna, V, Austria-Hungary, have invented a new, original, and ornamental Design for a Wall-Covering, of which the following is a specification.

This invention relates to a new original and ornamental design for wall covering.

The single figure illustrates a surface view of a portion of a wall covering containing my new design.

The leading features of the design consist of a plurality of panels each of which is

roughened in imitation of graining similar in general effect to wood graining; together with said panels are raised border strips, the surfaces of each strip being roughened to harmonize with the design of the panels embraced within said border strips.

I claim:

The ornamental design for wall covering, as described and shown.

Signed at Vienna.
